UNITED STATES PATENT OFFICE

GEORGE W. POWERS, OF CLEVELAND, OHIO

CRIBBING

Application filed August 23, 1930, Serial No. 477,445. Renewed October 16, 1931.

This invention relates to the art of cribbing for use in connection with retaining walls and the like.

One object of the present invention is to devise a cribbing structure in which the stretcher and header members are hollow and are formed of sheet metal of such nature as to be proof against deterioration from the natural elements.

10 Another object consists in devising an improved means of interconnection between the overlapping portions of the stretcher and header members so that the same may be readily assembled and disassembled.

15 Another object consists in providing a filler means for insertion between the stretcher members so as to prevent escape of the material therebetween.

20 Other objects will appear from the following description and claims when considered together with the accompanying drawing.

Fig. 1 is a perspective view illustrating one means of interconnection between the stretcher and header members; Fig. 2 is a modification of Fig. 1; Fig. 3 is a perspective view illustrating the manner of applying a filler between the stretcher members; Fig. 4 is a perspective view of a portion of a filler; Fig. 5 is an elevation of a modified form of filler; Fig. 6 is a plan view of a modified form of stretcher member to be used in connection with the filler shown in Fig. 5; Fig. 7 is an end view of a still further modified form of filler; Fig. 8 is an elevation thereof; Fig. 9 is a top plan view of such modified form of filler; Fig. 10 is a diagrammatic cross-sectional view indicating the general assembly of the stretcher and header members.

According to the present invention, the 40 stretcher members 1 and the header members 2 are formed of sheet metal, each of such members being formed of a single sheet layer which is formed into the desired hollow shape and the edge portions thereof welded in overlapping relation at the corner. In the present case, the stretcher and header members are shown as of square cross-section throughout their entire extent, although it is to be understood that any other particular shape 45 or design may be adopted; as, for instance,

these members throughout the greater portion of their extent may be of cylindrical form and their overlapping portions formed of square cross-section so as to facilitate the interlocking engagement of the same.

55 In the actual construction of the stretcher and header members, they are first formed into the particular shape and the joints of the overlapping edge portions are welded, and there are welded also to these members 60 the connecting means to be hereinafter described. Then, as the final step, the stretcher and header members are galvanized so as to render them proof against the natural elements. Any other form of rust-proof metal 65 may be used.

70 There may be employed various forms of connecting means between the overlapping portions of the stretcher and header members, the present disclosure being merely for 70 purposes of illustrating one general type of connection which may be adopted for either temporary or permanent connection between the members. In any event, the hollow stretcher and header members are reinforced 75 throughout the regions of their overlapping portions by means of the plugs or inserts 3 which are placed within each of these hollow members. These inserts may consist of 80 metal, wood, or other suitable material which will not only serve to reinforce against vertical compressive stresses the overlapping portions preferably of these members which are called upon to sustain the maximum strain, but these inserts serve also as a means of excluding the natural elements from the inside 85 of the hollow members. These inserts may extend to any point desired within the hollow members, although it is sufficient for 90 them to extend only to a point corresponding with the limits of the overlapping engagement between the stretcher and header members. For example, in the arrangements shown in Figs. 1 and 2, it is sufficient for the 95 inserts within the ends of the stretcher members to extend only half the distance of the insert within the end of the header member since the stretcher members are arranged in staggered joint relation. Concrete inserts may be used.

In the form illustrated in Fig. 1, the header member is provided upon the top and bottom thereof with the channel member 4 which is welded thereto. The side flanges of these channel members serve to receive the stretcher members which are engaged within the same either at the middle portion thereof or in staggered arrangement as herein illustrated. These channel members 4 are of such dimensions that the stretcher members may be conveniently seated therewithin for effective engagement, while at the same time permitting disassembly of the entire cribbing structure, if so desired.

15 In Fig. 2, the channel members 4 are disclosed as being secured to a cap member 5 which seats snugly over the end portion of the header member 2 and which has a closed end for engagement over the previously applied insert 2. The cap member may be welded in such position, it being understood that all of the several parts of the engaging means are secured in proper position prior to the galvanizing of the members as above explained.

20 Under certain conditions, it is deemed advisable to provide a filler means between the stretcher members so as to prevent the slipping of loose material such as silt, etc., through the cribbing. Such a filler may be in the form of a channel member 6 of sheet metal form which is placed between the stretcher members and which has its middle face substantially flush with the outer surface of the 25 stretcher members. This form of filler has its edge portions flanged, as indicated at 6^a, so as to engage about the corner portions of the upper and lower stretcher members. In this way, the filler is maintained in position even more securely by the force of the 30 material within the cribbing, and there may be provided also the strip or strips 7 welded to the flanges 6^a as a means of bracing the upper and lower portions of this form of filler.

40 45 Another form of filler consists of a single flat sheet of metal 8 provided with integrally formed ears 8^a upon the bottom and top edges thereof. These ears are adapted to be received in the corresponding slots 9 in the top and bottom of the stretcher members. These 50 slots are herein shown as being located substantially midway between the front and back of the stretcher members.

A still further form of filler is illustrated 55 in Figs. 7, 8, and 9 which show a sheet metal channel member with integrally formed ears on the top and bottom flanges thereof for interlocking engagement within corresponding 60 slots formed and positioned in the top and bottom of the stretcher members. These channel members may be so positioned between the stretcher that the main wall of the filler will be flush with the front surface of the stretcher members or these fillers may be 65 located at any other desired point between

the front and back of the stretcher members.

The various forms of fillers will also be galvanized so as to render them rust-proof after being formed into the desired shape.

73 By virtue of the hollow metal construction herein set forth, the cribbing structure here presented can be formed up with comparative ease and can be set in place for permanent location or can be disassembled at any time with the same degree of convenience. Because of the protection afforded against attack of the natural elements, the stretcher and header members in the present invention are calculated to have considerably longer life than the forms of structure heretofore employed. 77 This cribbing structure can be manufactured at a reasonable figure and possesses a high degree of reliability and efficiency as well as comparatively long life.

80 What I claim is:

1. A cribbing structure comprising hollow stretcher and header members, and closure caps for engagement over and about the overlapping portions of the headers, said caps having channel portions extending 90 transversely of the top and bottom of the header members so as to provide interlocking engagement between said members.

2. A cribbing structure comprising hollow sheet metal stretcher and header members having the ends thereof formed to provide flat load bearing walls extending in parallelism, said members being arranged to have said load bearing walls in overlapping load bearing relationship, means for securing said ends in assembled load bearing relationship and insertable reinforcing means positioned within said members and contacting with interior surfaces of said flat load bearing walls to thereby increase the resistance of said header and stretcher ends to compressive stresses.

95 3. A cribbing structure built of stretcher and header members comprising sheet metal body members formed with hollow open ends and having said ends formed to provide a flat load bearing wall connecting side walls extending in parallelism, said members being arranged in the structure to have said load bearing wall and said side walls thereof in overlapping load bearing relationship, means for securing said overlapping ends in assembled load bearing relationship and sheet metal closure means secured to said overlapping ends of said members and contacting with said flat load bearing walls and serving to close the ends of said hollow sheet metal members.

100 4. A cribbing structure built of stretcher and header members comprising sheet metal body members formed with open ends and having said ends formed to provide a flat load bearing wall and side walls extending in parallelism, said members being arranged 105 to have said load bearing wall and said side

walls in overlapping load bearing relationship, means for securing said overlapping ends in assembled load bearing relationship and insertable reinforcing means positioned within said overlapping ends of said members and contacting with the interior surfaces of said flat load bearing walls to thereby increase the resistance of the ends of said hollow sheet metal members to compressive stresses.

5. A cribbing structure comprising hollow sheet metal stretcher and header members having the ends thereof formed to provide flat load bearing walls extending in horizontal parallelism, said members being arranged to have said load bearing walls in overlapping load bearing relationship, means mounted on the header members and engaging the stretcher members for securing said ends in assembled load bearing relationship and insertable reinforcing means positioned within said members and contacting with interior surfaces of said flat load bearing walls to thereby increase the resistance of said header and stretcher members to compressive stresses wherever the header and stretcher members are engaged by said securing means.

6. A cribbing structure comprising hollow sheet metal stretcher and header members having at one or more points intermediate the ends thereof flat load bearing wall portions in parallel spaced relationship connecting side walls extending in parallelism, said members being arranged in the structure to have said load bearing wall portions and said side walls thereof in overlapping load bearing relationship, and reinforcing means associated with said load bearing wall portions and said side walls in the load bearing position to carry part of the vertical compressive stresses.

7. A cribbing structure comprising hollow sheet metal stretcher and header members having at one or more points intermediate the ends thereof flat load bearing wall portions in parallel spaced relationship connecting vertical walls, said members being arranged in the structure to have said load bearing wall portions and said vertical walls in overlapping load bearing relationship, and reinforcing means associated with said load bearing wall portions and said vertical walls in the load bearing position to carry part of the vertical compressive stresses.

8. A cribbing structure comprising hollow sheet metal stretcher and header members having at one or more points intermediate the ends thereof flat load bearing wall portions in parallel spaced relationship connecting vertical walls, said members being arranged in the structure to have said load bearing wall portions and said vertical walls in overlapping load bearing relationship, and sheet metal reinforcing means associated with said load bearing wall portions and said vertical walls in the load bearing position to carry part of the vertical compressive stresses.

tical walls in the load bearing position to carry part of the vertical compressive stresses.

9. A cribbing structure comprising hollow sheet metal stretcher and header members having at one or more points intermediate the ends thereof flat load bearing wall portions in parallel spaced relationship, spacing means including a plurality of vertical walls for transmitting the load from one load bearing wall to the other, said members being arranged in the structure to have said load bearing wall portions in overlapping load bearing relationship.

10. A cribbing structure comprising substantially tubular stretcher and header members, means for closing the exposed open ends of the tubular headers, and portions extending from said means for positioning the cribbing members above or below the header.

11. A cribbing structure comprising substantially tubular horizontally extending stretcher members assembled in vertical spaced relationship, and a filler plate having a vertical face adapted to close the space between the stretcher members, said filler plate having edge flanges extending normal to the face for securing the plate to the members.

12. A cribbing structure comprising substantially tubular horizontally extending stretcher members, assembled in vertical spaced relationship, said members having top, side and bottom walls, the top and bottom walls having openings therein, and a filler plate having a vertical face adapted to close the space between the stretcher members, said filler plate having tongues projecting from the upper and lower edges thereof, said tongues being adapted to enter the openings in the walls.

13. A cribbing structure comprising header and stretcher members substantially tubular in cross-section, said members having at one or more points thereof horizontally extending load bearing walls lying in parallel spaced relationship, said members having reinforcing means associated with said load bearing walls to carry part of the vertical compressive stresses, and said members being arranged to have said load bearing walls and reinforcing means in vertical load bearing relationship.

In witness whereof, I hereby affix my signature.

GEORGE W. POWERS.
